DESIGN FOR A COMBINED TWINE CUTTER AND SUPPORT

Sidney Futterman, Bronx, N. Y.

Application November 30, 1938, Serial No. 81,477

Term of patent 3½ years

To all whom it may concern:

Be it known that I, Sidney Futterman, a citizen of the United States and resident of Bronx, in the county of Bronx and State of New York, have invented a new, original, and ornamental Design for a Combined Twine Cutter and Support, of which the following is a specification, reference being had to the accompanying drawing forming part thereof, in which:

Fig. 1 is a perspective view of a combined twine cutter and support showing my new design.

Fig. 2 is a perspective view thereof showing the cutter separated from the support.

I claim:

The ornamental design for a combined twine cutter and support, as shown.

SIDNEY FUTTERMAN.
